UNITED STATES PATENT OFFICE.

JOHN S. FARLEY, OF CINCINNATI, OHIO.

CLOTHES-PIN.

1,176,210.

Specification of Letters Patent. Patented Mar. 21, 1916.

Application filed February 26, 1915. Serial No. 10,777.

To all whom it may concern:

Be it known that I, JOHN S. FARLEY, a citizen of the United States, and a resident of Cincinnati, in the county of Hamilton and State of Ohio, have invented certain new and useful Improvements in Clothes-Pins, of which the following is a specification.

My invention relates to clothes pins and fastening devices of a similar character; the object being to provide such an article of simple and sanitary construction and of convenient and effective operation.

My invention consists in the parts and in the details of construction and arrangement of parts as will hereinafter be more fully described and claimed.

In the drawing: Figure 1 is a side elevation of a clothes pin embodying my invention; Fig. 2 is an edge elevation of the same; Figs. 3 and 4 are side elevations of pins showing modifications of the binding means, and Fig. 4 also showing a modification of the upper end or loop of the pin; Figs. 5, 6 and 7 are side elevations of the lower end parts of pins, showing modifications of the lower ends; Fig. 8 is a view showing the pin in side elevation but with its members spread to pass over a clothes line, and illustrating the manner of handling the pin, and the upper parts of the pin being also represented in dotted lines in their positions before or after the pin has passed over the clothes line; Fig. 9 is a perspective view of part of a line and part of a garment or other article hung on the line with my improved pin gripping and holding the article on the line; Fig. 10 is a horizontal cross section on the line $x-x$ of Fig. 1, the binding means or washer being shown in full plan view; Fig. 11 is a similar cross section on the line $y-y$ of Fig. 3; and Fig. 12 is a similar cross section on the line $z-z$ of Fig. 4.

My improved clothes pin is constructed of a single piece of metal wire or other suitable resilient material bent in its middle to form two symmetrical members 2 and 3. The member 2 crosses under the member 3 at a point 4 at a proper distance from the middle bend 1 to allow a loop to be formed, which may be merely a plain loop 5 as shown in Figs. 1, 2 and 3, and Figs 8 and 9, or may comprise a coil 5' as shown in Fig. 4. In either instance, such a loop constitutes a suitable handle for the clothes pin. After the member 2 crosses under the mem-

ber 3 at 4, the members 2 and 3 diverge and then converge, crossing again at a point 6, but here the member 2 crosses over the member 3 instead of under as at the point 4. 60 The members 2 and 3 then again diverge and converge to cross at the point 7, the member 2 at this point 7 crossing over the member 2 as it did at the point 6. From the crossing point 7 the members diverge again 65 to a suitable distance, and then are extended substantially parallel for a sufficient distance to form proper guides 8 and 9 on the ends of the members 2 and 3, respectively, for the entrance of the clothes and the line 70 between these members. The ends of the members 2 and 3 are bent laterally outward and upward and then inward, forming eyes 10 and 11, respectively, so that these ends thus formed permit uninterrupted entrance of the clothes. The extreme ends of the wire or other material are preferably brought very close to the straight standing parts 8 and 9, respectively, in forming these eyes, so that these parts cannot catch in 80 the fabric of the clothes.

The ends may have other formations such as in Fig. 5, where the ends are left straight and the guides 8' and 9' are merely slightly diverged downward; or as shown in Fig. 85 6 where the end parts 10' and 11' are merely curved outwardly at their respective sides of the pin, bringing the extreme ends of the wire or other material substantially at right angles to the axis of the pin and to the 90 direction of entrance and recession of the clothes; or as shown in Fig. 7 where the ends are left straight but are provided with balls or heads 10'' and 11'' to provide the proper 95 smooth entrance to the pin.

While I thus show several modifications of the terminal parts of the pin, the formation of the main piece of each part 2 or 3 is in each instance the same as above described, it being understood, as before alluded to, that any such pin may have the complete coil such as the coil 5' shown in Fig. 4, or merely the plain bend between the two parts 2 and 3 as in the loop 5 shown in the other views. In each case the operation will be 100 substantially the same except that one form of terminal part may be preferred over the other by different makers or users of the pins for reasons of economy or facility of use of the pin, whichever may be considered 110 the more important. The same considerations will determine whether the coil or the

loop 5' shall be used, or the plain bend of the other examples.

In any of these constructions, the crossing and recrossing of the members 2 and 3 are seen to form an inclosure 12 adapted to embrace the line and the clothes when on the line as illustrated in Fig. 9, this inclosure lying between the crossing points 4 and 6. Between the crossing points 6 and 7 are the 10 curves 13 and 14 on the respective parts 2 and 3, the one curve 13 lying over the other curve 14 and being adapted to slide off of it, and the two curves being adapted to separate completely and allow them to pass down 15 over the clothes 15 and line 16 to admit the line and the adjacent part of the clothes into the space 12, whereupon the curves 13 and 14 again come together by virtue of the resiliency of the wire or other material of 20 which the pin is composed, and will grip the clothes 15 below and adjacent to the line 16, as shown in Fig. 9. While the overlapping curves 13 and 14 are thus allowed to 25 separate edgewise to permit the entrance of the clothes and line to the inclosure 12, they are maintained in operative proximity by the contact of the members 2 and 3 at the crossing point 4. This contact is thus opposed to the separation of the overlapping 30 curves 13 and 14, due to the fact that the member 2 crosses under the member 3 at the point 4 and over the member 3 at the points 6 and 7.

When the clothes and line begin to engage 35 with the parts 2 and 3 immediately below their curves 13 and 14 to force them apart, there will also be a tendency for the pin to twist around with the plane of its broadest dimension nearly parallel with the line 16, 40 thus separating the parts 2 and 3 in a direction at right angles to that in which they should be separated according to the above described operation. Such twisting of the pin is inconvenient and disagreeable to the 45 user, and because of the spreading of the parts of the pin in the wrong direction they are liable to be permanently distorted from the crossing point 4 downward even to the extent of being rendered unsuitable for use. 50 Also, the parts are liable to separate at the points 4 and admit the clothes and line to the interior of the loop 5, where they would not be properly held.

I have discovered that if a reinforcing 55 member be provided around the parts 2 and 3 in the region of the crossing point 4, the above serious defects will be eliminated or avoided. Thus as shown in Figs. 1 and 2, and Figs. 8, 9 and 10, this reinforcing or 60 binding member consists of the flat ring or washer 17, the aperture 18 of which is of ample diameter to permit entire freedom of movement of the parts 2 and 3 when they are spread as shown in Fig. 3, and yet effectively reinforcing and binding these parts

together in direction at right angles to the direction of proper spreading of the parts, as is best seen in the cross section in Fig. 10. It will be seen that the circular shape of the aperture 18 is well suited for the purpose, 70 since the sides of this aperture engage with the respective outer sides of the parts 2 and 3 but engage with these parts at no other point, leaving the parts free for relative movement in the proper direction. As the parts spread as shown in Fig. 8, the loop 5 becomes shortened, the crossing point of the parts 2 and 3 rising above the point 4. With the binding member or washer 17 having the aperture 18 amply large, and being thus 75 freely movable with the crossing parts 2 and 3, this washer 17 will slide up on the parts 2 and 3, as plainly shown in Fig. 8, where the dotted lines indicate the positions of the parts 2 and 3 and the washer 17 when the 80 pin is closed. It will be seen that the washer 17, when the pin is spread open, as indicated by the solid lines in this view, has risen a considerable distance. This rising and falling of the binding member or washer 85 17 permits the free relative movement of the parts 2 and 3 in the proper direction and avoids undue springing or bending of the parts 2 and 3 in the region of and above the space 12, while practically all distortion in 90 the direction of the line 16 is eliminated. While the binding member or washer 17 thus slides up and down loosely, it effectively reinforces the parts 2 and 3 in their 95 clamping or binding operation upon the 100 clothes 15 on the line 16, in addition to protecting these parts against distortion while the pin is being applied to and withdrawn from the clothes and line.

In Figs. 3 and 11, the binding member 105 consists of a simple wire ring 17' with its ends brought very close together, as shown in Fig. 11. Such a binding member will be satisfactory as long as the ends do not separate and allow the member to become too 110 loose on the pin or to come off of the pin.

In Figs. 4 and 12, a second modification is shown in which the binding member consists of a very short tube 17'', which of course may be seamless and not liable to 115 become open like the wire ring 17', while being more compact and neat than the washer 17 of the first described example. In some instances, however, the operation of such a tube will be inferior to that of the washer 120 17 or of the ring 17', apparently due to its greater extent along the pin and the wider separation of its bearing surfaces upon the parts 2 and 3, which are thus at increased 125 distances from the crossing point of the parts 2 and 3, whereas it appears that the bearing of the binding member on the parts 2 and 3 should be as close to the crossing point as possible.

Such pins may be slid along the line with 130

the clothes if the clothes are to be moved from one part of the line to the other, or slid off of the clothes, allowing the clothes to be removed from the line, and may be left on the line when the clothes are removed and the line is taken down and rolled up, and thus not so great a proportion of the pins will be lost. This, in addition to their increased durability as compared with wooden pins affords an economy in their use, while their positive clamping or gripping operation, as insured by the reinforcing or binding member, makes them satisfactory for use in places and under conditions where the ordinary wooden pin or any other inexpensive pin will be found inadequate. Where the lines are run out from high buildings or on shipboard, the wind in either case is generally so strong that no ordinary pin can be depended upon to hold the clothes upon the line, and garments are frequently blown away and lost where attempt is made to use pins which do not have adequate gripping power. Also, the entirely open construction of my pin makes it easy to keep clean and sanitary.

Having fully described my invention what I claim as new and desire to secure by Letters Patent is:

30 A clothes pin formed of a single piece of wire bent in its middle to form two members which cross each other to form the upper end of a line and clothes embracing inclosure, said members forming a loop

or handle for the pin above said point of crossing, and below said crossing converging and again crossing each other, but in opposite positions relative to each other at their point of crossing and thereby forming the other end of said inclosure, said members beyond their second point of crossing having outward curves to form oppositely disposed overlapping clothes gripping parts, and being further extended to cross each other at a third point and from there diverging and then being continued in the same general direction, to form the entrance guides to the pin, said members being forced apart as the clothes on the line engage through the entrance guide with the gripping parts, whereby the clothes and line enter between the gripping parts into the inclosure, and a reinforcing and binding member embracing said parts at their point of crossing above said inclosure, fitting said parts loosely and adapted to slide up on said parts as their gripping parts are separated and the point of their crossing rises, and to slide down when the parts come together, but engaging said parts to reinforce and bind them against spreading in a direction at right angles to their proper direction of spreading.

JOHN S. FARLEY.
